[57] CLAIM

The ornamental design for a safety mirror fender guide, as
shown and described.

DESCRIPTION

FIG. 1 is a front elevational view of a safety mirror fender
guide showing my new design;

FIG. 2 is a rear elevational view thereof;

FIG. 3 is a top plan view thereof;

FIG. 4 is a bottom view thereof;

FIG. 5 is a side elevational view thereof, as seen from the
right side relative to FIG. 1; and.

FIG. 6 is a perspective view thereof, the broken line showing
of a portion of an automobile fender being for illustrative
purposes only and forming no part of the claimed design.
